Primary Examiner — Steven J Czyz

(57) CLAIM

The ornamental design for a bag, as shown and described.

DESCRIPTION

1. Bag

1.1 : Perspective

1.2 : Front

1.3 : Back

1.4 : Right

1.5 : Left

1.6 : Top

1.7 : Bottom

1.8 : Front View of the bag shown in an alternate state

1.9 : Enlarged View of a portion of the left side of the bag

The bag comprises a body, a handle and a shoulder strap; the body has a rectangular base, two side gussets and a top opening around which there is a belt sewn to the rear wall of the body and whose ends extend in front of the front wall of the body and are provided with parts of a connecting mechanism; a first end of the belt has a retaining prong and a belt buckle with two pyramidal formations, and the other end has two pyramidal formations and several openings that can be hooked to the prong of the first end.

1 Claim, 9 Drawing Sheets
